BALLOON

Bernard Sayers, Sharp Lane,
Newport, N.J. 08345

Filed Dec. 31, 1974, Ser. No. 537,733

Term of patent 14 years

Int. Cl. D12—07

U.S. Cl. D12—71

FIG. 1

FIG. 2

FIG. 1 is a side elevation of a balloon showing my new design, and the broken lines indicating a basket and supporting lines of a type oftentimes used with such balloons; and

FIG. 2 is a top plan view.

I claim:

The ornamental design for a balloon, as shown and described.
